UNITED STATES PATENT OFFICE.

THEODORE P. PANAGOS, OF SAN FRANCISCO, CALIFORNIA.

CRAVAT-SUPPORTER.

1,247,570.

Specification of Letters Patent. Patented Nov. 20, 1917.

Application filed July 24, 1916. Serial No. 111,032.

To all whom it may concern:

Be it known that I, THEODORE P. PANAGOS, a citizen of the United States, residing at San Francisco, in the county of San Francisco and State of California, have invented 5 certain useful Improvements in Cravat-Supporters, of which the following is a specification, reference being had therein to the accompanying drawing.

- 10 This invention relates to improvements in cravat and necktie supporters, one object of the invention being the provision of a supporter which acts as a form upon which the tie may be arranged and by means of which 15 it is unnecessary to have a portion of the tie passed around the neck band of the collar, it being possible to form the tie upon the supporter and then adjustably attach the same to the front collar button so that the 20 tie will be properly supported in close contact with the collar.

A further object of this invention is the provision of a device of this character which is simple, inexpensive and durable in construction and thoroughly efficient and practical in use.

In the accompanying drawings:

Figure 1 is a perspective view of the present device used in connection with a lay-down collar.

Fig. 2 is a perspective view of the supporter *per se*, dotted lines illustrating the position of a four-in-hand tie thereon.

Fig. 3 is a plan view of the blank of the 35 main supporting member.

Fig. 4 is a rear elevation thereof showing an elastic and button hole engaging member in place.

Fig. 5 is a modified form of blank.

Fig. 6 is a sectional view on the line 6—6 of Fig. 5.

Referring to the drawings, the numeral 10 designates the support or frame which is made from a single sheet of material, either 45 sheet metal, paper, celluloid, or the like, the

same being provided with the two divergent terminals 11 and the depending terminal 12, said depending terminal being provided with the rounded concavity 13 at its junction with the divergent terminals and being channeled throughout its length to produce the flattened end 14.

Formed in the flattened end is an elongated opening 15, while formed thereabove 55 is a circular opening 16, there being a circular opening 17 formed in the enlarged de-

pressed portion and the two openings 18 formed thereabove in the relatively flat portion of the supporter.

The elastic cord 19 is threaded through 60 the respective openings as illustrated, and where the same projects through the elongated opening at the flattened end 14 of the device, it is passed through the openings 20 of the collar button engaging plate 22, said 65 plate being normally disposed at the rear of the lower end of the supporter so as to engage and slip over the head and shank of the collar button 23 supporting the laydown collar 24 as illustrated.

70

When it is desired to regulate the tension of the elastic cord the ends of the latter, which are reversely trained through the adjustable sleeve 25, can be pulled upon, thereby shortening the length of the cord, and 75 this sleeve 25 will frictionally hold the ends of said cord and thus in this manner regulate the tension thereof relative to the collar button engaging member.

Where this device is used in connection 80 with laydown collars, the cravat or tie 26 is positioned as illustrated in Fig. 2, the collar button engaging plate, after the divergent terminals have been pressed firmly 85 between the ends of the collar and at the junction between the neck band and flaps thereof, is placed upon the button so as to place the elastic cord under stress, thus holding the tie in position and pulling the lower end of the support against the shirt bosom, 90 thus holding the tie against upward creeping movement and flat upon the wearer.

Where the present tie support is used in connection with standing collars, the hooked terminals or lugs 27 are formed integral 95 with the divergent terminals upon the lower edge thereof, so that these terminals will engage the lower edge of the collar between the collar band and the lower edge of the collar, and thus support the tie in proper 100 position.

What I claim as new is:—

In a device of the kind described, in combination, a tie support having a depending terminal so as to be substantially T-shaped, 105 said support and terminal being bulged out so as to provide a continuously channeled member, said channeled member having its channel restricted in width between its ends, said channeled member being formed at its 110 upper end and near its lower end with an opening and with a slot at its lowermost

end, said support having spaced apart openings directly above said member, an elastic cord having its terminals passed through the openings of said support, both terminals being passed into the first and second openings of said channeled member so as to be mounted close together snugly within the restricted portion of the channel of said mem-

ber and passing through said slot, a button engaging plate to which the free ends of 10 said terminals are secured, and a sleeve on said plate through which said terminals reversely extend and in which they are frictionally held.

In testimony whereof I affix my signature. 15
THEODORE P. PANAGOS.
